(57) CLAIM

I claim the ornamental design for the storage shed with windows, as shown and described.

DESCRIPTION

FIG. 1 is a front elevational view of a storage shed with windows;

FIG. 2 is a top plan view of the storage shed with windows;
FIG. 3 is a left side elevational view of the storage shed with windows, the right side of which is identical; and,
FIG. 4 is a rear elevational view of the storage shed with windows.

The bottom of the storage shed with windows is plain and unornamented.
